VOTING MACHINE

Ransom F. Shoup, Ardmore, Pa., assignor to The
Shoup Voting Machine Corporation, Philadel-
phia, Pa., a corporation of Delaware

Application June 10, 1941, Serial No. 397,446

11 Claims.

(Cl. 235—55)

This invention relates to voting machines and more especially to voting machines of the so-called horizontal type.

In certain states, the election laws provide that with respect to certain offices, for example, representation in the general assembly, each voter has the right to cast from one to three ballots for any candidate and also the voter has the right to distribute his three ballots in any manner that he may desire among one to three candidates of his choice. Such provision is for the purpose of properly proportioning and balancing the relative strength of the political parties as it may be indicated in the general assembly. The voter may cast his entire three ballots for one candidate; he may cast two ballots for one candidate and his remaining ballot for a second candidate; he may cast one and one-half ballots for each of two candidates; or he may cast a single ballot for each of three candidates. He may limit his choice of candidates to a single party or he may split his choice among the candidates of two or more parties.

An object of this invention is to equip the so-called horizontal type of voting machine with mechanism to enable it to be used for cumulative voting according to the election laws above referred to.

Other objects, novel features and advantages of this invention will become apparent from the following specification and accompanying drawings, wherein:

Fig. 1 is a fragmentary front elevation of a horizontal type voting machine arranged for balloting on candidates for representatives in general assembly;

Fig. 2 is a fragmentary rear view showing the interlocking straps and main grouping channel;

Fig. 3 is an enlarged fragmentary view through the main grouping channel showing the interlocking straps and the location of one compensator;

Fig. 4 is a section taken on the line 4—4 of Fig. 3 and shows the manner of mounting a compensator in the main grouping channel;

Fig. 5 is a section substantially on the line 5—5 of Fig. 7 and shows the manner of mounting and connecting the mechanism with the straps of the main grouping channel;

Fig. 6 is a perspective view of the cumulative mechanism showing the group controls in neutral position;

Fig. 7 is a rear view showing the cumulative mechanism attached to the main grouping channel with one group control in position of use;

Fig. 8 is a front elevation of the cumulative mechanism showing a second group control in position of use;

Fig. 9 is a view similar to Fig. 8 showing a third group control in position of use;

Fig. 10 is a view similar to Fig. 2 of a modified arrangement, and

Figs. 11, 12 and 13 are views similar to Figs. 1, 8 and 7 respectively illustrating said modification.

In the drawings, 10 indicates a keyboard of a horizontal type voting machine having several horizontal rows of indicators 11, but only three such rows being shown. Each indicator 11, through mechanism well-known in the art, is capable of recording a vote on a suitable register subsequent to being moved from the position shown in the drawings downwardly to a position such that one end of the indicator is directed toward the name of a candidate for office generally indicated by the letters 12 in channels 13.

In Fig. 1, the voting machine is shown to be set up for three parties. Each horizontal row is allocated to one party and the name of each party candidate appears several times in his party row.

Although, as illustrated, each party has three candidates running, it is to be understood that any party may have a lesser number than three. Each candidate's name (irrespective of party) appears twice in the non-party group designated X and once each in the non-party groups designated Y and Z, the candidates being designated by the letters A to I inclusive.

That portion of the voting machine connected with the cumulative mechanism comprises a plurality of interlocking straps 15, each of which is formed with a ledge or shoulder 17 and each of

which has its lower end formed with a neck 18 terminating in an enlarged head or wedge 19 projecting into a main grouping channel 20 forming a part of the voting machine and comprising spaced plates 21 equipped with horizontal channels 22 receiving the enlarged ends of rollers 24. Between each pair of rollers 24 (Fig. 3) there are located the neck portions of two straps 15, the

enlarged heads or wedges 19 being located within the channel and beneath the rollers. Upon actuation of an indicator 11, one interlocking strap 15 is raised causing its head or wedge 19 to move upwardly between a pair of rollers with

concomitant movement of said rollers laterally apart and limiting to a predetermined degree further lateral displacement of the rollers upon subsequent raising of further interlocking straps.

Lateral displacement of the rollers 24 and the grouping of the interlocking straps 15 and their

respective indicators is obtained through the use of grouping pins 25 and compensators 26. As shown in Fig. 2, the plates 21 are provided with openings 27 for the purpose of receiving grouping pins 25 which project transversely of the channel and are in the lateral path of rollers 24. Three grouping pins 25 are located in certain openings 27 to provide three non-party groups X, Y and Z, as indicated in Fig. 2. In group X, there are six lesser groups of interlocking straps, while in each of groups Y and Z, there are three lesser groups of interlock straps. The number of lesser groups in group X is the product of the greatest number of candidates for any party and the number of unit votes each voter is allowed while the number of lesser groups in each of groups Y and Z is equal to the greatest number of candidates of any party. Although the drawings show the machine to be set up for three candidates for each party, the same arrangement of lesser groups will prevail if the machine is set up with one or more parties having a lower number of candidates than another party. The number of straps in each of the lesser groups depend upon the number of horizontal rows of indicators located on the face of the machine. In the present instance, nine interlocking straps are contained in each lesser group as the machine is equipped with nine horizontal rows of indicators.

Each indicator in one vertical column of the machine is connected with one strap in a strap group. The voting machine as set up in Fig. 1 permits each voter to cast three ballots. The spacing of the rollers 24 is such that six interlocking straps of group X may be raised. Therefore, the possible lateral displacement of the rollers 24 of this group is decreased by inserting three compensators 26 in group X substantially as shown in Figs. 2, 3 and 4. Each compensator inserted serves to prevent one of the interlocking straps from being raised by occupying the space the corresponding head 19 could occupy between any pair of rollers. The provision of three of these compensators in group X reduces to three the number of interlocking straps in said group which may be manipulated. A voter entitled to register three votes may, by manipulation of certain of the indicators of group X, cast one, two or three votes for candidates of his party or split his party vote in the same manner.

In each of groups Y and Z, three are three lesser groups of interlocking straps. The rollers 24 in each group are limited in lateral displacement by two group pins 25 and since these pins are located to include three strap groups only three vote could be cast. However, since it is possible to cast three votes in group X, provision is made that in group Y, only two straps can be actuated so that the voter may divide his ballot into one and one-half votes for each of two candidates and in group Z provision is made that only one interlocking strap can be actuated so that the voter, by actuating a single indicator, may cast his three ballots for a single candidate. The restriction of group Y to two candidates is accomplished by inserting one compensator 26 into group Y while the restriction of group Z to a single candidate is accomplished by inserting two compensators 26 into said group.

Mechanism is provided for attaching the cumulative mechanism to the voting machine adjacent the main grouping channel. Such mechanism is indicated by the reference numeral 30 and includes a frame 31. Adjacent the lower

edge of the frame is a pair of supporting brackets 32 terminating in upstanding flanges 33 and adjacent the brackets 32 are longer brackets 35 terminating in upstanding flanges 36. Spacing studs 37 project from one face of the frame and elements 39 formed from or attached to the frame provide pivotal support for hooks 40 projecting through suitable openings 41 in the frame 31. One end of each hook is pivotally joined to a clamping screw 43 projecting through a support 44 on the frame 31. A portion of the screw adjacent the support 44 is threaded and receives a nut 45. The mechanism 30 is mounted on one face of the main grouping channel by engaging the flanges 36 of brackets 35 with the inner face of one of the channel plates, the flange 33 of the bracket 32 abutting the other face of the plate and the studs 37 also abutting the outer face of the grouping channel. Suitable slots 46 are provided in one of the channel plates to receive the ends of the hooks 40. When the mechanism is in place, the nut 45 is rotated, raising the screw 43 and moving the hook downwardly into engagement with the plate through which it projects. In order to locate this mechanism to control any group of indicators, it must be attachable on any plate on the main grouping channel. Therefore, a plurality of slots 46 are provided in the outer face of the main grouping channel to permit entrance of the hooks 40.

On the frame 31 are three movable members which are interlocked to prevent simultaneous actuation of any two. On the face of the frame 31 remote from the channel 21 are mounted brackets 48 from which six supports 49 project. One pair of supports mounts a shaft 50 on which are fixed a pair of spaced arms 51 extending over the frame 31 and overlying the space between said frame and the channel 20. The ends 50 of the arms 51 are connected by a rod 52 which is provided with a plurality of reduced diameter portions 53. A second pair of supports 49 pivotally mount a second shaft 50a to which are secured three arms 51a having their free ends connected by a rod 52a having a plurality of reduced diameter portions 53a. A third pair of supports 49 mounts a shaft 50b on which is fixed a pair of spaced arms 51b connected by a rod 52b having a plurality of reduced diameter portions 53b. The shaft 50, arms 51 and rod 52 constitute one movable member which is associated with that portion of the cumulative mechanism related to group Y, heretofore mentioned and indicated in Fig. 1. Shaft 50a, arms 51a and rod 52a constitute the second movable member associated in the same manner with that portion of the cumulative mechanism related to group X. The shaft 50b, arms 51b and rod 52b constitute the third movable member similarly associated with that portion of the cumulative mechanism related to group Z. The rod 52a is provided with six reduced portions 53a, this number corresponding to the duplicate listing of the candidates in group X on the face of the voting machine while the rods 52a and 52b are provided with three reduced portions 53a and 53b respectively corresponding to the candidate listing in each of groups Y and Z. Apertures 55, 55a and 55b are provided in arms 51, 51a, and 51b for a purpose later to be described.

Pivotal mounted on the face of the frame 31 adjacent the grouping channel 20 are arms 60a and 60b, the free ends of which are fitted with pins 61a and 61b, projected through curved slots 62a and 62b in the frame 31. These slots per-

mit limited rotation of the free end of each arm about its pivotal support. In order that the arms 60a and 60b may have controlled movement, sliding links 64, 64a and 64b are provided and are formed with slots 65, 65a and 65b through which pins 61a and 61b on the frame 31 project. The links 64a and 64b are on the same side of the frame 31 with the arms 60a and 60b while the link 64 preferably is on the opposite side of said frame. The links 64a and 64b are provided with end surfaces which are engageable with the pins 61a and 61b respectively, while the link 64 is provided with end surfaces which are engageable with the left pin 61a and the right pin 61b respectively. The left pin 61a and the right pin 61b are long enough to project into the path of the link 64 while the remaining pins 61a and 61b do not extend beyond the rear face of the plate 31. Thus, when the left arm 60a is moved clockwise from the position shown in Fig. 9 to the position shown in Fig. 8 by mechanism hereinafter to be described, left pin 61a thereof engages the left end of link 64a moving it laterally to the right and causing the right arm 60a to be moved from the position shown in Fig. 9 to the position shown in Fig. 8. The reverse of this operation is initiated by the right arm 60a which causes the bar 64a to rotate the left arm 60a. Similar reciprocation of the link 64b is effected by the pins 61b of the arms 60b while similar reciprocation of the link 64 is effected by the pins 61a and 61b of the outer arms 60a and 60b as is evident from an inspection of Fig. 6.

Pivottally mounted on the same side of the frame 31 are three cam plates 68, 68a and 68b. The cam plate 68 comprises two cam arms 69' and 69'' and a finger 70 while the cam plates 68a and 68b comprise cam arms 69a and 69b and fingers 70a and 70b respectively. The cam arm 69' and the cam arm 69a extend toward each other while the cam arm 69'' and the cam arm 69b extend toward each other. The cam arms 69', 69'', 69a and 69b are formed with inclined meeting edges 72' and 73', 72'' and 73'', 72a and 73a, and 72b and 73b respectively. The cam arms 69a and 69b are of identical shape but oppositely directed and the left cam arm 69' is of identical shape with both the cam arms 69a and 69b and is identically directed with the cam arm 69b. The right cam arm 69'' is of identical shape with the cam arm 69' but is oppositely directed and inverted. The relation of the arms 69' and 69'' is such that the surface 73' and the right surface 73'' are in alinement. Because of the inversion of the cam arm 69'' the pivot of the pin 61b of the left arm 60b underlies the surface 73' and said cam arm 69b is located above its pin 61b to facilitate actuation of such arm by the cam arm 69'' and actuation of the cam arm 69'' by said pin. The arrangement of the arms 60a and the outer arm 60b is such that they are gravity biased toward the positions in which they engage the surfaces 72a and 72b respectively, and a spring 60' preferably is provided for biasing the inner arm 60b toward the position in which it engages the surface 72'' although such spring may be omitted. The fingers 70, 70a and 70b project respectively into slots 55, 55a and 55b to effect movement of the cam plates 68, 68a and 68b respectively by the arms 51, 51a and 51b.

Figs. 5 and 6 illustrate the means by which the cumulative mechanism is operably connected with the interlocking straps of the voting machine. A pair of straps 80 are spacedly connected by a

lug 81 and directly above the lug each strap 80 is formed with a flange 82. Beneath the lug 81 the straps are continued parallel for a short distance and then bent inwardly and joined together to form a connecting link 84, the lower end of which terminates in a hook 85. The straps 80 are spaced apart a distance to enclose a group of nine interlocking straps 15, the flanges 82 being located to the rear of the interlocking straps. The lug 81 is adapted to rest upon the ledges or shoulders 17 of the group of interlocking straps, while the hook 85 is engaged in one of the recesses 54, 54a or 54b of the rods 53, 53a or 53b respectively.

As indicated in Fig. 1, each set of correspondingly identified indicators of each horizontal row is allocated to the same group of candidates and in a general election, each row of indicators is allocated to a single political party. The counter associated with each indicator is advanced one digit for each indicator operation, but each digit of a counter of group X is counted as a single vote for a candidate, while each digit of a counter of group Y is counted as a vote and a half for a candidate and each digit of a counter of group Z is counted as three votes for a candidate. A voter may cast a ballot for candidate A by actuating the proper indicator in any group. If he actuates an A indicator in group X, he locks out the indicators of groups Y and Z but may still actuate two more indicators in group X. If he actuates an indicator of group Y, he locks out the indicators of groups X and Z but may still actuate a second indicator in group Y. If he actuates an indicator in group Z he locks out the indicators of groups X and Y and also locks out the remaining indicators of group Z.

Assume that a voter elects to cast his three votes for a single candidate. He actuates one indicator in group Z and elevates the rod 53b through the connection of the link 84 and the hook 85 from the position shown in Fig. 7 to the position shown in Fig. 6. Elevating this rod raises the cam arm 69b causing the pin 61b of the right arm 60b to move off the inclined surface 73b onto the surface 73b. As the right pin 61b is moved, it strikes the right ends of the sliding links 64 and 64b causing said links to move to the left. The left end of the link 64 engages the pin 61a of the left arm 60a, moving said pin to occupy a position directly over the surface 73a of the cam arm 69a. As the cam plates 68 and 68a are connected respectively to the rods 53 and 53a of groups Y and X respectively, both of these groups are locked as the rods 53 and 53a are now locked (Fig. 6) against being elevated and in consequence no one of the indicators on the face of the voting machine in either group X or group Y may be actuated to raise any interlocking straps in either group since these straps are connected through the hooks 55 with the rods 53 and 53a. If the elector had chosen to manipulate an indicator in group X as part of casting one vote for each of three candidates or two votes for one candidate and one vote for a second candidate, the cam arm 69a (Fig. 8) would have been elevated and the cam arms 68 and 68b locked thereby locking the rods 53a and 53b to prevent any of the indicators in groups Y and Z from being actuated. If the elector had chosen to actuate an indicator in group Y, the cam plate 68 (Fig. 9) would be moved clockwise, thus caus-

ing the pin 61a of the right arm 60a to move off the left inclined surface 73 and the pin 61b of the left link 66b to move off the right inclined surface 73, thereby causing leftward movement of the link 64a and rightward movement of the link 64b. The pin 61a of the left hand link 66a would thereupon occupy a position directly over the surface 73a of the cam plate 68a and the pin 61b of the right link 66b would occupy a position directly over the surface 73b of the cam plate 68b, thereby locking the rod 53a and 53b against elevation.

In some communities, the cumulative voting law limits the voter to equally dividing his vote among the candidates. Figs. 10 to 13 illustrate the above mechanism set up to comply with such cumulative voting requirements. With the arrangement shown in these figures, the voter may cast a single vote for each of three candidates, a one and a half vote for each of two candidates and three votes for a single candidate but cannot cast two votes for one candidate and a single vote for another candidate. In this set-up, the arrangement of indicators is identical in each of the three groups X, Y and Z and each candidate's name appears but once in group X as well as in each of groups Y and Z. The number of lesser groups of interlocking straps in group X is three instead of six as in Figs. 1 to 9 and no compensator 28 is used in said group. Also, while the two-section arrangement of Figs. 1 to 9 for group X may be used, it is preferred to use the single section arrangement shown in Fig. 12. With this arrangement, the voter utilizes group X only for dividing his vote evenly among three candidates with one vote to each candidate. The groups Y and Z are arranged as described in connection with Figs. 1 to 9 and the operation is the same except that the voter cannot use group X to divide his ballot into two votes for one candidate and one vote for a second candidate.

It is of course understood that various modifications may be made in the apparatus above described without in any way departing from the spirit of the invention as defined in the appended claims.

I claim:

1. A mechanism for use with a voting machine in cumulative voting and being operable by and serving to control movement of selected non-party groups of interlocking straps of said machine, said mechanism comprising a hook-like element for each strap group supported by said group for actuation by any strap of the group, a frame located adjacent said interlocking straps, a trio of pivotally movable members on said frame representing three non-party groups, the hook-like elements of certain interlocking strap groups being engaged with one of said members and the hook-like elements of a part of the remaining interlocking strap groups being engaged with another of said members and the hook-like elements of the rest of the interlocking strap groups being engaged with the third member, a swingable unit for each member connected thereto for movement therewith, a bar associated with each pair of units for slidable movement between two positions in one of which it renders inoperative one unit associated with said bar and the non-party groups of interlocking straps connected thereto and in the other of which it renders inoperative the remaining unit and the non-party groups of interlocking straps connected thereto, and means co-operating with each unit

for moving each bar associated therewith in one direction upon actuation of said unit.

2. A mechanism for use with a voting machine in cumulative voting and being operable by and serving to control movement of selected non-party groups of interlocking straps of said machine, said mechanism comprising a hook-like element for each strap group supported by said group for actuation by any strap of the group, a frame located adjacent said interlocking straps, a trio of pivotally movable members on said frame representing three non-party groups, the hook-like elements of certain interlocking strap groups being engaged with one of said members and the hook-like elements of a part of the remaining interlocking strap groups being engaged with another of said members and the hook-like elements of the rest of the interlocking strap groups being engaged with the third member, a swingable unit for each member connected thereto for movement therewith, a slidable bar associated with each pair of units, a pair of pivoted arms associated with each bar, a pin carried by each arm for engagement by a unit and by one end of said bar to effect linear movement of the bar upon rotary movement of a unit to render inoperative each of the remaining units and the non-party groups of interlocking straps connected thereto.

3. In a voting machine, a plurality of groups of interlocking straps, a trio of pivotally movable members, hook-like elements connected to the straps of each group, the hook-like elements of certain interlocking strap groups being engaged with one member and the hook-like elements of a part of the remaining interlocking strap groups being engaged with another member and the hook-like elements of the remaining interlocking strap groups being engaged with the third member, a swingable unit connected to each member for movement therewith, a movable bar extending between each unit and each remaining unit, and means co-operating with each unit to effect movement of each bar associated therewith toward the remaining unit associated with said bar to render inoperative said last-named unit and the groups of interlocking straps connected thereto.

4. In a voting machine, a plurality of groups of interlocking straps, a trio of pivotally movable members, hook-like elements connected to the straps of each group, the hook-like elements of certain interlocking strap groups being engaged with one member and the hook-like elements of a part of the remaining interlocking strap groups being engaged with another member and the hook-like elements of the remaining interlocking strap groups being engaged with the third member, a swingable unit for each member connected thereto for movement therewith, a bar associated with each pair of units for slidable movement between two positions in one of which it renders inoperative one unit associated with said bar and the groups of interlocking straps connected thereto and in the other of which it renders inoperative the remaining unit and the groups of interlocking straps connected thereto, and means co-operating with each unit for moving each bar associated therewith in one direction upon actuation of said unit.

5. In a voting machine, a plurality of groups of interlocking straps, a trio of pivotally movable members, hook-like elements connected to the straps of each group, the hook-like elements of certain interlocking strap groups being engaged

with one member and the hook-like elements of a part of the remaining interlocking strap groups being engaged with another member and the hook-like elements of the remaining interlocking strap groups being engaged with the third member, a swingable unit for each member connected thereto for movement therewith, a slidable bar associated with each pair of units, a pair of pivoted arms associated with each bar, a stud carried by each arm for engagement by a unit and by one end of said bar to effect linear movement of the bar upon rotary movement of a unit to render inoperative each of the remaining units and the groups of interlocking straps connected thereto.

6. In a voting machine, a trio of swingable units, a set of groups of interlocking straps connected to each unit, an interlock individual to each set of groups of interlocking straps connected to each unit with each said interlock set to permit actuation of a different number of straps in each set, a bar associated with each pair of units for slidable movement between two positions in one of which it renders inoperative one unit associated with said bar and the groups of interlocking straps connected thereto and in the other of which it renders inoperative the remaining unit and the set of groups of interlocking straps connected thereto, and means cooperating with each unit for moving each bar associated therewith in one direction upon actuation of said unit.

7. In a voting machine, a trio of swingable units, a set of groups of interlocking straps connected to each unit, an interlock individual to each set of groups of interlocking straps connected to each unit with each said interlock set to permit actuation of a different number of straps in each set, a slidable bar associated with each pair of units, a pair of pivoted arms associated with each bar, a stud carried by each arm for engagement by a unit and by one end of said bar to effect linear movement of the bar upon rotary movement of a unit to render inoperative each of the remaining units and the set

45 of groups of interlocking straps connected thereto.

8. In a voting machine, a trio of swingable units having spaced parallel axes, the center unit having two cam arms of which one is directed toward one end unit and the other of which is directed toward the other end unit and each end unit having a cam arm directed toward said center unit, slidable links extending between each

10 unit and each remaining unit, a pair of pivoted arms for each link having pins engageable with the opposite ends of said link and with the cam arms at the opposite ends of said link, and an actuating member connected to each unit.

15 9. In a voting machine, a trio of swingable units having spaced parallel axes, the center unit having two cam arms of which one is directed toward one end unit and the other of which is directed toward the other end unit and each end

20 unit having a cam arm directed toward said center unit, slidable links extending between each unit and each remaining unit, a pair of pivoted arms for each link having pins engageable with the opposite ends of said link and with the cam

25 arms at the opposite ends of said link, a group of interlocking straps connected to each unit, and an individual interlock for the straps of each group with the three interlocks set to permit actuation of one, two and three straps respectively.

30 10. In a voting machine, the combination according to claim 8 characterized by the axes of said swingable units being horizontal, said slid- 35 able links being horizontal and said pivoted arms being biased for movement to locate the pins thereof in engagement with the corresponding cam arms.

40 11. In a voting machine, the combination according to claim 9 characterized by the axes of said swingable units being horizontal, said slid- 45 able links being horizontal and said pivoted arms being biased for movement to locate the pins thereof in engagement with the corresponding cam arms.

RANSOM F. SHOUP.
